Primary Examiner — Nicole C Shiflet(74) *Attorney, Agent, or Firm* — Dinsmore & Shohl LLP(57) **CLAIM**

The ornamental design for an electronic device with graphical user interface, as shown and described.

DESCRIPTION

The FIGURE is a front view of an electronic device with graphical user interface showing the claimed design. The outermost dashed lines in the FIGURE show an electronic device having a display screen or portion thereof and form no part of the claimed design. The other dashed lines show portions of the graphical user interface that form no part of the claimed design.
